UNITED STATES PATENT OFFICE.

REINHOLD KRUMMING, OF MILWAUKEE, WISCONSIN.

LEAF AND COVER HOLDER FOR BOOKS.

1,090,632.

Specification of Letters Patent. Patented Mar. 17, 1914.

Application filed January 2, 1906. Serial No. 294,147.

To all whom it may concern:

Be it known that I, REINHOLD KRUMMING, of Milwaukee, Wisconsin, have invented a Leaf and Cover Holder for Books, of which 5 the following is a specification.

My invention relates to devices for holding books in open position without manual assistance, and particularly those books which are thick, narrow or stiff-backed and 10 tend strongly to close up of their own accord.

My invention is particularly applicable to books such as trade catalogues which are used by solicitors and commercial travelers 15 to set their wares before prospective customers, and more particularly to loose-leaf books having what is known as the telescopic back.

My invention will best be understood from 20 the following description taken in connection with the accompanying drawings, in which—

Figure 1 shows the simplest form of my book-holder, Fig. 2 shows a folding form of 25 Fig. 1, Figs. 3 and 4 are respectively a side and an end elevation of another form of book-holder, Figs. 5 and 6 are respectively an end and a side elevation of a form of my invention having a leaf-holding attachment, 30 Figs. 7 and 8 are respectively a plan and a longitudinal central section through a form similar to that of Figs. 5 and 6 but having an attachment similar to that of Fig. 2. Fig. 9 is a side elevation of a book with my 35 holder shown in Fig. 1 attached thereto to hold the book in open position, Fig. 10 is a perspective of a book showing the holder of Fig. 3 attached thereto, Fig. 11 is a side elevation of a book showing the holder of Fig. 5 and 6 in operative position thereon, 40 and Fig. 12 is an elevation of the back of a book having a holder-attachment in accordance with my invention permanently secured thereto.

That form of my invention which is shown 45 in Fig. 1 comprises a simple bar or strip of sheet metal or thin wood *a*, having a tongue *b* which is inserted into the crevice at the back of a book *B* (Fig. 9) between 50 the cover and leaves for the purpose of holding the back thereof upright on the table *A*; the ends of the bar *a* resting upon the table and preventing the back from falling over laterally. In such position, the back being 55 held vertical, the leaves will lie open in any desired position as illustrated in Fig. 9. In

stead of a solid sheet or plate the holder might be made from a wire having at the center an offset the shape of the tongue *b*, as will be obvious.

60

Fig. 2 shows a folding form of Fig. 1 comprising three leaves *a*¹, *a*², *a*³, which are pivoted together on a screw *c*, one of these leaves being inserted into the crevice at the back of the book and the whole folded up 65 into a small compass to put into the pocket.

The form shown in Figs. 3, 4 and 10 comprises a strip of sheet metal *d* bent into loop form as shown and having a bar *e* pivotally mounted on one lap thereof by a 70 rivet *f*. This form is adapted especially for loose-leaf books having covers *B*¹, *B*² with telescopic backs *g*, *g*¹, one of which overlies the other. The free lap of the strip *d* is inserted at the back between the two folds 75 *g*, *g*¹, as shown in the drawing, and the bar *e* lies parallel to the book-cover when not in use, and when it is desired to hold the book open it is turned into the position *d*' wherein it holds the back of the book upright in 80 the same manner as illustrated in Fig. 9. This form can also be used by inserting the free lap of the strip *d* into the crevice at the end of the book-cover in the same manner as the tongue *b* of Fig. 1.

85

The form shown in Figs. 5 and 6 comprises a bar *h* which is arranged to be inserted into the crevice at the back between the cover and leaves in the same manner as the tongue *b* in Fig. 1, said bar having one end 90 bent up at right angles to form a tab *h*¹ as shown; a post *i* pivoted to the tab *h*¹ by a rivet *j* and having its upper end bent back obliquely in an offset *i*¹, said offset having a pair of pintle-lugs *i*² at its opposite sides; 95 and a spring-clip *k* having perforated ears *k*¹ which turn on the lugs *i*². The spring-clip *k* has further a spring-tongue *k*² either cut out of the metal thereof as shown in the drawing, or else riveted to the free end 100 of the clip as may be preferred, the end of the tongue *k*² passing through an opening *i*³ in the post *i*. The rear end of the clip *k* is bent over to form a thumb-piece *k*³. It will be clear that the effect of the tongue *k*² 105 is to draw the clip *k* down, because when raised into the position *k*¹, for instance, the tongue *k*² will be sprung out from the body of the clip. Consequently the clip *k* acts as a finger or holder to hold down the leaves 110 of the book on which it may rest. This form may be used in either of two positions

shown respectively in Figs. 8 and 11. In Fig. 8 the book B lies open with the back upright and the clip *h* in the crevice between the leaves thereof. In Fig. 11 the 5 back of the book is parallel to the table and the upper cover and some of the leaves turned back through 180°, the post *i* being rotated into a position at right angles to that shown in Fig. 5 so as to enable the clip 10 *h* to overlie the open leaves at a point near the bend.

The form shown in Figs. 7 and 8 is similar to that of Fig. 6 except that there are 15 added thereto a pair of strips *m*¹, *m*², which are pivoted upon a screw *n* fixed in an extension *o* formed on the end of the bar *h* beyond the tab *h*¹. The bars *m*¹, *m*² fold up parallel to the bar *h* when the instrument is put in the pocket, and when in use 20 they may be extended to hold the book in the position of Fig. 8, or may remain collapsed to hold it in the position of Fig. 11.

In Fig. 12 is shown a book with a holder 25 permanently attached thereto, the holder consisting of two bars *p*, *p*' which are pivoted upon rivets *q* on the back of the book. The bars *p*, *p*' fold up against the book-cover as shown by the dotted lines when not 30 in use, and when it is to be held open the bars *p*, *p*' are extended to hold the book-cover upright on the table as shown in Fig. 9.

From the above description it will be

clear that my holder is not confined to any special form of detail but is subject to many 35 changes and modifications while retaining the principle thereof.

Having thus described my invention, what I claim as new and desire to secure by Letters Patent, is:

1. A device for holding books in open position comprising a flat bar adapted to be inserted into the back between the outer cover and binding of the book projecting at one end of the back, and wings on said bar 45 extending at right-angles to said bar beyond the sides of the back and lying in the plane of the back when said bar is so inserted.

2. A device for holding books in open position comprising a flat bar adapted to be 50 inserted into the back between the outer-cover and binding of the book projecting at one end of the back, and wings on said bar extending at right angles to said bar beyond the sides of the back and lying in the plane 55 of the back when said bar is so inserted; said wings being each pivoted upon said bar whereby they are adapted to fold into superposed relation when said bar is withdrawn.

In witness whereof I have hereto set my hand this thirtieth day of December, 1905.

REINHOLD KRUMMING.

In presence of—

GEORGE WETMORE COLE,
ALF. WALLBER.
